(57) **CLAIM**

The ornamental design for a card with chip, as shown and described.

DESCRIPTION

FIG. 1 is a front view of a card with chip showing the claimed design;

FIG. 2 is a rear view thereof;

FIG. 3 is a right side view thereof, the left side view being the same;

FIG. 4 is a top view thereof, the bottom view being the same;

FIG. 5 is a front view of a second embodiment thereof;

FIG. 6 is a rear view thereof;

FIG. 7 is a right side view thereof, the left side view being the same;

FIG. 8 is a top view thereof, the bottom view being the same;

FIG. 9 is a front view of a third embodiment thereof;

FIG. 10 is a rear view thereof;

FIG. 11 is a right side view thereof, the left side view being the same;

FIG. 12 is a top view thereof, the bottom view being the same;

FIG. 13 is a front view of a fourth embodiment thereof;

FIG. 14 is a rear view thereof;

FIG. 15 is a right side view thereof, the left side view being the same; and,

FIG. 16 is a top view thereof, the bottom view being the same.
